UNITED STATES PATENT OFFICE.

WILLIAM DELOS O'CONNOR, OF EVERETT, WASHINGTON.

CARBURETER.

1,187,375.

Specification of Letters Patent. Patented June 13, 1916.

Application filed May 5, 1915. Serial No. 26,135.

To all whom it may concern:

Be it known that I, WILLIAM DELOS O'CONNOR, a citizen of the United States, residing at Everett, in the county of Snohomish and State of Washington, have invented new and useful Improvements in Carbureters, of which the following is a specification.

This invention relates to carbureters for use in connection with internal combustion engines, the object in view being to produce a device of the character referred to which will efficiently mix different grades of liquid fuel with air and heat such mixture so that the engine may be operated by gasolene, distillate, kerosene, alcohol, or any other fuel oil that when combined with air may be exploded when confined in the combustion chamber of an engine.

A further object of the invention is to provide in connection with the heater or main body of the device, means for regulating the supply of air and fuel thereto and so disposing the air and fuel inlets and the discharge which forms the engine intake, as to obtain a thorough mixing of the air and fuel oil before the same reaches the combustion chamber or chambers of the engine.

With the above and other objects in view, the invention consists in the novel construction, combination and arrangement of parts, as herein described, illustrated and claimed.

In the accompanying drawings:—Figure 1 is a side elevation showing the apparatus of this invention applied to an internal combustion engine. Fig. 2 is a vertical sectional view of the same, illustrating the construction of the heater and the fuel chamber, and the relative arrangement of the several parts of the apparatus. Fig. 3 is a cross section on the line 3—3 of Fig. 1 taken about centrally of the heating chamber. Fig. 4 is a sectional view on the line 4—4 of Fig. 1 taken adjacent to one end of the heater. Fig. 5 is a longitudinal section through a modified form of heater.

Referring to the drawings A generally designates an internal combustion engine the exhaust pipe of which is indicated at 1 and the intake pipe of which is indicated at 2.

In carrying out the present invention and in order to adapt the engine to be operated by fuel oils of different grades, I employ a generator, the main section of which consists of a fuel mixture heater designated generally at B and the same comprising an outer and preferably cylindrical or tubular shell

or container 3, an inlet header 4 at one end thereof and an outlet header 5 at the opposite end thereof and an outlet header 5 at the opposite end thereof, the headers 4 and 5 being shown as threaded upon the opposite ends of the shell 3. The exhaust pipe 1 enters the header 4 and the exhaust delivered into the shell 3 of the heater by said exhaust pipe passes through a tube or plurality of tubes 6 extending longitudinally of the heater and inclosed by the shell 3, said tubes 6 being connected at their opposite extremities to the head plate 7 within the headers 4 or 5 so that the exhaust gases from the engine will be forced to pass through the tubes 6 from the inlet header 4 to the outlet header 5 and from thence preferably through an extension exhaust pipe 8 to the atmosphere.

9 designates an air inlet pipe one end of which is connected to and in communication with the shell 3, the opposite end of said pipe being left open to admit air drawn into the shell 3 by the suction of the piston or pistons of the engine A during the intake or suction stroke of the piston or pistons as readily understood by those familiar with the art to which this invention appertains. Associated with the air inlet pipe 9 is a liquid fuel chamber 10 into the top of which leads a fuel feed pipe 11 connected thereto by a union 12. The chamber 10 is provided with an inlet bore 13 terminating in a valve seat 14 with which co-operates a valve 15 having a stem 16 working through a guide 17 screwed into a tubular boss 18 on the under side of a screw cap or plug 19 which closes the upper end of the chamber 10. Within the chamber 10 is arranged a float 20 which upon rising comes in contact with the stem 16 of the valve 15, forcing the latter upwardly to a closed position and thereby shutting off the further ingress of fuel oil. The chamber 10 is provided with an outlet or discharge passage 21 which communicates at the point 22 with the chamber 10 near the bottom of the latter, the discharge end 23 of said passage being arranged directly in the air pipe 9 where the discharge of the fuel oil is regulated by an adjustable manually controlled valve 24 resembling the well known needle valve.

It will be understood from the foregoing description that upon the unseating of the valve 24, the air sucked into the heater through the pipe 9 by the action of the

engine, carries with it fuel oil in a quantity proportionate to the extent to which the valve 24 is opened. The chamber 10 is shown as provided with a lateral extension 5 connected directly to and receiving the air inlet pipe 9. The pipe 11 is branched as shown, the same being illustrated as provided with two branches 26 and 27 leading to compartments 28 and 29 of a fuel tank, 10 the feed pipes 28 and 29 being controlled respectively by manually operated valves or stop cocks 30 and 31. By this means, the engine may be started on gasoline and after the vaporizer becomes sufficiently heated, the 15 gasoline may be cut off and fuel oil of lower grade may be used in place thereof. Adjacent to the outlet header 5, the heater is provided with an auxiliary air inlet pipe 32 controlled by an automatic auxiliary air inlet 20 valve 33 which is adjustable in the ordinary way for regulating the tension of the valve to admit more or less air in accordance with climatic changes and other conditions. At a point between the air inlet pipe 9 and the 25 auxiliary air inlet pipe 32, the engine intake pipe 2 communicates with the interior of the heater through the outer shell 3.

It will now be understood from the foregoing description taken in connection with 30 the accompanying drawings, that a constant level of liquid fuel is maintained in the chamber 10 by the operation of the float 20 in conjunction with the inlet valve 15. In starting the engine it is preferable to use 35 oil of a more volatile nature such as gasoline, the chamber 10 being preferably made of such capacity as to hold only enough gasoline to effect the running of the engine for a period of several minutes or until the 40 container B becomes heated to an extent which will cause it to effectively raise the temperature of kerosene or oil of a lower grade than gasoline.

In operation, the exhaust gases from the 45 engine A are conducted by the exhaust pipe 1 into the header 4 and thence through tubes resembling a tubular boiler into the outlet header 5 and thence out through the extension exhaust pipe 8. This highly heats the 50 tubes within the shell 3 and on account of the small size and capacity of the pipe 9 only a small amount of air is drawn inwardly through said pipe 9, sufficient to take up the requisite amount of fuel oil from the 55 charge passage 21 of the fuel chamber 10 to feed the engine with the necessary mixture. The remainder of the necessary quantity of air is admitted through the auxiliary air inlet pipe 32 and it will be noted that the 60 point of exit of the air and fuel oil is at an

approximately medial point in the length of the vaporizer and located between the pipes 9 and 32. Therefore, the combined air and oil drawn in through the pipe 9 meet the auxiliary air delivered by the pipe 32 at the 65 junction of the engine intake pipe 2 with the heater. Therefore, the oil and air are thoroughly mixed in passing through the intake pipe 2 to the combustion chamber or chambers of the engine. The pipe 2 is 70 shown as equipped with the usual throttle valve 34 to regulate the supply of mixture to the engine.

It will, of course, be understood that the device hereinabove described may be used 75 in combination with any internal combustion engine and it will further be understood that the size of the entire apparatus may be varied to suit any engine in connection with which it is used. Therefore, various changes 80 may be made in the form, proportion and minor details of construction of the device without departing from the principle or sacrificing any of the advantages of the invention.

In lieu of the heater hereinabove described, where the device is to be used upon the engine of an automobile, I may employ the simple form of heater illustrated in Fig. 5 consisting of a hollow cylindrical 90 body or sleeve 3' which fits over the exhaust pipe 8' and is formed with the end walls or heads 7', 2' and 9' designating pipes corresponding with the pipes 2 and 9 of the construction illustrated in Fig. 1. This is a 95 very simple form of heater and is applicable around the exhaust pipe of the internal combustion engine of a motor vehicle.

What I claim is:—

An attachment for an internal combustion 100 engine, comprising a heater embodying a container shell, head plates adjacent to the ends thereof, inlet and outlet headers enclosing said head plates and forming exhaust inlet and outlet chambers, exhaust conducting tubes connecting said head plates, a fuel mixture inlet pipe communicating with said shell adjacent to one end thereof, a valved auxiliary air inlet communicating with said shell adjacent to the other end 105 thereof, and an engine intake pipe leading from said shell at a point between said mixture inlet pipe and said auxiliary air inlet.

In testimony whereof I affix my signature in presence of two witnesses:

WILLIAM DELOS O'CONNOR.
